(57) **CLAIM**

The ornamental design for a staircase, as shown and described.

DESCRIPTION

FIG. 1 is a front perspective view of a staircase showing our new design;

FIG. 2 is a front view thereof;

FIG. 3 is a rear view thereof;

FIG. 4 is a right side view thereof;

FIG. 5 is a top view thereof; and,

FIG. 6 is a bottom view thereof.

The broken lines in the Figures show portions of the staircase or environment that form no part of the claimed design.

The dot-dash lines in the Figures show unclaimed boundaries that form no part of the claimed design.

The oblique shade lines in the Figures show transparency and not surface ornamentation.

1 Claim, 4 Drawing Sheets
